Claims priority, application Germany May 13, 1952

4 Claims. (Cl. 260—448)

This invention relates to the manufacture of trialkylaluminium compounds. These compounds are also referred to as "aluminium trialkyls."

It is known that the so-called "alkylaluminium sesquihalides," i. e. mixtures of alkylaluminium dihalides and di-alkylaluminium monohalides, can be produced from metallic aluminium and alkyl halides as exemplified by the following equation:

Substantially homogeneous dialkylaluminium monohalides may be produced by the action of alkyl halides on an alloy of 70% aluminium and 30% magnesium according to Grosse and Mavity, Journal of Organic Chemistry (1940), 5, 110 and 119. This alloy contains aluminium and magnesium approximately in the molar ratio of 2:1, so that the reaction may be represented by the equation:

The formation of the aluminium trialkyls would appear to require the use of an aluminium-magnesium alloy which corresponds at least to the composition Al_2Mg_3 . Nothing has hitherto become known of any attempts to carry out the reaction

using such an alloy. Such attempts may well have been discouraged by the knowledge that on increasing the magnesium content of the alloy, the behaviour of the alloy towards the undiluted alkyl halide approaches that of magnesium itself. It is known, moreover, that magnesium reacts with alkyl halides smoothly and satisfactorily only in the presence of ether (Grignard-like reaction). In fact, stable trialkylaluminium etherates are easily obtained from alloys containing predominantly magnesium, e. g. from electron metal, and alkyl halides under the conditions of the Grignard reaction i. e. in solution in ether. (E. Krause and B. Wendt, Berichte der Deutschen Chemischen Gesellschaft, 56, 466 (1923). Ether-free aluminium trialkyls alone are not obtained in this manner, as the ether cannot be removed from the etherates by simple means. Thus the problem of producing ether-free aluminium trialkyls directly from alkyl halides and suitable aluminium alloys (which would follow the known formation of tetraethyllead from PbNa_4 and 4 molecules of ethyl chloride) has hitherto remained unsolved. The ether-free aluminium trialkyls have recently become important as polymerisation catalysts for olefins.

It has now been found that magnesium-aluminium alloys having a composition in the region of 57-65% magnesium and 43-35% aluminium (Mg_3Al_2 to Mg_2Al) can, despite their high magnesium content, be reacted with alkyl halides in the absence of ether to yield only or mainly aluminium trialkyls. The alloys specified are extremely brittle and can, therefore, be powdered to a very fine dust without difficulty. They are suitably added in this form in the process of the invention. In addition

a little iodine or alkylaluminium sesquibromide may be added to facilitate the commencement of the reaction. The reaction may be carried out in the presence of inert solvents, particularly saturated aromatic or hydro-aromatic hydrocarbons, but is best carried out direct with the alkyl halide in undiluted state. In the latter case, though, the demand on the stirring mechanism which has to be provided in the reaction vessel is fairly heavy, since the reaction products contain a large quantity of magnesium halide and accordingly easily form solid lumps so that a too weak stirrer sticks. This difficulty may be overcome by working in a rotating drum which contains grinding bodies. The aluminium organic compounds produced are recovered from the solid or semi-solid reaction mixtures by distillation or solvent extraction.

The first reaction products mostly still contain some halogen, e. g. the product from Mg_3Al_2 and ethyl bromide contains from 5 to 10%, and rarely up to 15%, of halogen which corresponds to a content of about double this percentage of diethylaluminium bromide. This halogen content may easily be removed by a further treatment with the very finely powdered aluminium-magnesium alloy at a temperature of 150-170° C., whereupon pure, halogen-free aluminium trialkyls are obtained in high yields.

Example 1

1.3 kg. of finely powdered aluminium-magnesium alloy containing 40% Al and 60% Mg are mixed with 1 kg. ethylbromide in a small vessel furnished with a powerful stirring mechanism and an effective reflux cooler. After stirring for 1-2 hours—commencement of the reaction may be hastened by the addition of iodine or some aluminium bromide or "ethylaluminiumsesquibromide"—reaction takes place with self-heating. A further 3.8 kg. of ethyl bromide is then added over a period of about 6 hours, intensive stirring being continued throughout. The stirring is continued so long as spontaneous reaction is noticeable (up to 24 hours). During this time the stirrer will occasionally stop. The mix may now be worked up by distilling off the aluminium organic product which has formed. In this case a distillate is obtained which consists mainly of triethylaluminium, but which also contains 7-15% of bromine. It is better to heat the vessel, after spontaneous reaction has ceased, for 20 hours at 160° C. and then to distill. In this manner a halogen-free distillate may be obtained directly. Yield: 1.2-1.4 kg. triethylaluminium or about 70-85% of the theoretical yield.

Example 2

The procedure described in Example 1 is followed, but the reaction is carried out in a pressure-sealed reaction vessel, and instead of ethyl bromide a solution of 4 kg. of methyl bromide in 5 litres of hexane is used. After cessation of the spontaneous reaction, any of the following procedures may be followed:

(a) A further 5 litres of hexane is added to the reaction vessel and the mixture is stirred. After allowing settlement to take place, the hexane solution of trimethylaluminium is drawn off. Following this—always with complete exclusion of air—the hexane is distilled off in a column, the residue is mixed with 200 kg. of the finely powdered magnesium-aluminium alloy and this mixture is heated at 160° C. for 10 to 20 hours whilst stirring. Thereupon the trimethylaluminium is distilled off in vacuo. Yield: 60-75% of the theoretical yield.

(b) The hexane is distilled off and the residue heated as in Example 1 for 20 hours at 160° C. Following this, it is possible either to distill off the trimethylaluminium immediately in vacuo or—after cooling—to extract

as described under (a) above, in this case conveniently with pentane.

(c) In the presence of the originally used hexane, heating is carried out under pressure and agitation at 160° C., and the whole worked up according to (a) and (b).

Example 3

The procedure of Example 1 or 2 is followed, but three kg. of ethyl chloride are used instead of the 4.8 kg. of ethyl bromide. In each case a pressure boiler suitable for use up to about 20 atm. and furnished with a pressure reflux condenser is employed, from the top of which the gases of the C₂ series (ethylene, ethane), which accumulate in the vessel and cause a gradual inadmissible rise in pressure, are released from time to time. These gases are formed by secondary reactions. The whole further process is described in Example 1.

Example 4

In the conversion described in this example, of 552 g. of butyl iodide with 75 g. of aluminium-magnesium alloy, the final reaction mixture consists of 420 g. of magnesium iodide and 200 g. of tributylaluminium. From this disparity between solid phase and liquid, difficulties may arise, which may be avoided by the following procedure. A stout-walled, completely welded, cylindrical, steel pot of about three litres content (diameter of base=height of cylinder) serves as the reaction vessel. The cylinder jacket carries a portion of steel tube welded in as neck. About 75 g. of the aluminium-magnesium alloy (40:60) is introduced into the pot, which has previously been flushed out with nitrogen. Furthermore a number of grinding pellets, consisting conveniently of pieces of 6-edged steel of 10-15 mm. diameter and cut to length=width are also introduced. The pot is mounted on a suitable rocking table and the neck connected with

the necessary stationary fittings via a flexible metal tube.

Whilst shaking continuously, 550 g. of n-butyl iodide are admitted to the pot at a speed which maintains the reaction temperature at about 100° C. Following this, the temperature is maintained at this level for some time and is then raised to 160° C.

The tributylaluminium thus formed is easily extracted from the reaction mass by means of a hydrocarbon solvent (under nitrogen).

10 We claim:

1. Process for the production of aluminium trialkyls free from substantial quantities of halogen which comprises reacting an alkyl halide at a temperature between 30 and 170° C. with a magnesium-aluminium alloy containing from 57 to 65% of magnesium and from 43 to 35% of aluminium in an ether-free reaction mixture and recovering the aluminium trialkyl thus formed.

2. Process according to claim 1, which comprises reacting an alkyl halide in the presence of an inert solvent, with a magnesium-aluminium alloy.

3. Process according to claim 2, in which said reaction is effected with a hydrocarbon as a solvent.

4. Process for the production of halogen-free aluminium trialkyl, which comprises reacting an alkyl halide at 25 a temperature between 30 and 170° C. with a magnesium aluminium alloy containing from 57 to 65% of magnesium and from 43 to 35% of aluminium in an ether-free reaction mixture, and thereafter treating the aluminium trialkyl thus formed with a finely divided magnesium-aluminium alloy of the composition specified above.
